(57) **CLAIM**

We claim the ornamental design for an aperture cover, as shown and described.

DESCRIPTION

FIG. 1 is a perspective view of an aperture cover showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is a perspective view of the design in a use environment engaged over the aperture of a vacuum separator. The broken lines in the figure drawings represents unclaimed environment only and form no part of the claimed design; and the dot-dash broken lines in the figure drawings represent an unclaimed boundary of the claimed design that forms no part thereof.
